UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

REGISTER, &c.

1,399,417.

Specification of Letters Patent.

Patented Dec. 6, 1921.

Application filed February 16, 1921. Serial No. 445,334.

To all whom it may concern:

Be it known that I, CURTIS HUSSEY VEEDER, a citizen of the United States, residing in the city of Hartford, in the State of Connecticut, have invented certain new and useful Improvements in Registers, &c., of which the following is a specification, reference being had to the accompanying drawing, forming a part hereof.

10 This invention relates particularly to the means for supporting registers of the type of that shown and other mechanisms and for effecting the connection therewith of the flexible shaft by which the register or other mechanism is actuated. The purposes of the invention are to avoid strain on the casing of the register or other mechanism either by the base plate or by the casing which incloses the usual worm gear or other driving 15 mechanism, to permit the angle of sight of the mechanism to be adjusted readily to suit the convenience of the observer, to permit the angle of the gear casing to be adjusted readily to suit the requirements of 20 the flexible drive shaft, and to permit both the driven mechanism and the driving mechanism to be removed without disturbing the base plate. The invention has been developed with particular reference to the 25 application to registers and counters and will be more fully explained hereinafter with reference to the accompanying drawing in which it is illustrated and in which—

30 Figure 1 is a view in elevation of a register with the present improvements applied thereto.

35 Fig. 2 is a view of the same as seen from the right hand in Fig. 1, with the end casing broken out and the driving gear partly in section.

40 Fig. 3 is a view in section on the plane indicated by the broken line 3—3 of Fig. 1 looking in the direction of the arrows.

45 Fig. 4 is a view in section on the plane indicated by the broken line 4—4 of Fig. 1, looking in the direction of the arrows.

50 Fig. 5 is a top view of the register, with the casing broken out and some parts of the register and the driving gear in section.

55 Fig. 6 is an end view of the register as seen from the left hand in Fig. 1.

The register *a* is of ordinary construction, having a cylindrical casing *b* within which are supported number wheels *c*, driving

mechanism *d* and a drive shaft *e*. The register is supported, as hereinafter described, upon a base plate *f*.

The left hand end plate *a'* of the casing has its cylindrical hub *a'* seated in a circular bearing formed by a pedestal *f'*, secured to the base plate, and a cap *f''*, detachably secured to the pedestal by screws *f''*. The right hand end plate *a''* of the casing has its cylindrical hub *a''* seated in a circular bearing which, in this instance, is formed by the split, cylindrical hub *g'*, *g''*, of the casing *g* which incloses the worm gearing by which the shaft *e* is driven. The split cylindrical hub *g'*, *g''* is in turn seated in a circular bearing formed by a pedestal *f''*, secured to the base plate *f*, and a cap *f'''* which is detachably secured by screws *f'''* to the pedestal. The hubs of the casing have a friction bearing in their seats and the casing is held from turning when the screws *f''*, *f'''* are tightened, but when the screws are loosened the casing can be rotated, with respect to the base plate and with respect to the gear casing so as to permit the angle of sight of the register to be adjusted to suit the convenience of the observer.

The gear casing *g* has a suitable bearing for a worm shaft *h* which engages a worm wheel *e'* on the shaft *e*, the casing being suitably chambered to receive the worm shaft and the worm wheel. The gear casing is formed in two parts, the hub *g'*, *g''* being divided in a diametrical plane and grooved, as at *g''*, to be held between the pedestal *f''* and cap *f'''* and embracing the hub *a''* of the casing end plate *a''*. When the screws *f'''* are loosened the gear casing can be rotated to permit the angle of the gear casing to be adjusted to suit the requirements of the flexible shaft and by tightening the screws the gear casing will be secured in adjusted position.

The gear casing *g* is formed with a split sleeve-like extension *g''*, which is provided with tangent screws *g''* and adapted to receive and have clamped therein the flexible steel tubing *i* of the flexible shaft *i'*. The worm shaft *h* is preferably formed with a polygonal socket *h'* to receive the similarly formed end of the flexible shaft *i'* so that all that is necessary to effect a coupling of the flexible shaft with the register is to insert the end of the flexible shaft in the socketed worm

2
shaft and to clamp the flexible shaft casing or tubing *i* in the split sleeve-like extension *g*⁴ of the gear basing *g*.

It will be observed that the gear casing 5 and register can be separated readily from each other and from the base plate without disturbing the latter.

I claim as my invention:

1. The combination of a mechanism to be 10 driven having a casing with end plates having cylindrical hubs, a gear casing having a split cylindrical hub to receive the hub of one of the casing end plates and a base plate

having a pedestal with a detachable cap to form a circular bearing for the cylindrical hub of the gear casing. 15

2. The combination of a mechanism to be driven, a base plate therefor having a pedestal with detachable cap to form a circular bearing and a gear casing having a split cylindrical hub seated in said circular bearing. 20

This specification signed this 9th day of February, A. D. 1921.

CURTIS HUSSEY VEEDER.
